UNITED STATES PATENT OFFICE

2,504,762

ADJUSTABLE HOLDER FOR WINDOW SHADES, CURTAINS, AND DRAPE

Samuel A. Vennare, Pittsburgh, Pa.

Application December 18, 1946, Serial No. 716,995

3 Claims. (Cl. 248—252)

1

My invention is directed more particularly to apparatus for mounting window shades, curtains and drapes at windows, the supporting elements therefor being vertically movable relative to the window frame.

Heretofore, brackets and the like which are vertically movable or adjustable at windows have commonly been applied to supporting elements secured to the exposed face of the window frame, to either side of and above the window opening, but such devices not only are frequently visible to an extent that is objectionable to the eye, but frequently the woodwork of the window frame is exposed, because it is difficult to extend the curtains and drapes far enough to each side of the window to completely cover the frame. Furthermore, when such devices are removed from a window frame, unsightly holes are left in the woodwork, and repeated placing and removal of such brackets or holders results in damage to the window frame.

My invention has for one of its objects the provision of an improved arrangement whereby window shade brackets, curtain rod supports and the like can conveniently be fastened to the edges of a window frame instead of to the exposed face thereof.

Another object of my invention is to provide an improved arrangement of supports, brackets, or the like for window coverings, whereby all of the face area of a window frame can readily be covered by curtains or drapes applied thereto.

Still another object of my invention is to provide an improved arrangement of vertically movable supporting brackets for shades, drapes and the like, at windows, whereby they may readily be raised and lowered for the placing and removal of the window coverings, or set at various heights to exclude sunlight from a lower portion of a window but to admit the light through the upper portion thereof.

In the accompanying drawings, Figure 1 is a face view of a window to which my invention has been applied; Fig. 2 is an enlarged sectional view taken on the line II—II of Fig. 1; Fig. 3 is a front elevational view showing the guide rails employed for the raising and lowering of the shade and curtain supporting brackets, together with the manner in which pulleys and ropes are applied thereto; Fig. 4 is an end view of one of the guide rails of Fig. 3; Fig. 5 is an enlarged inner face view of one of the carriers employed in the guide rails; Fig. 6 is an outer face view thereof; Fig. 7 is an edge view of the structure of Fig. 5; Fig. 8 is an enlarged perspective view showing one of the pair

2

of shade and curtain supporting brackets of Fig. 1; Fig. 9 shows the other bracket; Fig. 10 is an enlarged perspective view of one of the drape-supporting elements; Fig. 11 is a perspective view showing a pair of drape-supporting rods; Fig. 12 is a perspective view showing a modified form of the attaching elements used to connect the guide rails to a wall; Fig. 13 is an edge view of a modified form of guide rail; Fig. 14 is a cross sectional view of the guide rail of Fig. 13 and showing it connected to a wall; Fig. 15 is a perspective view of another form of guide rail; Fig. 16 is a perspective view of a slide bar therefor; Fig. 17 is a sectional view of this rail and bar in assembled relation, and Fig. 18 is a face view of a portion of the rail of Fig. 15.

For attachment to the edges of a wood window frame 9, the structure comprises a pair of vertical rails 10 and 11 flanged to form trackways as shown in Figs. 2 and 3. The rail 10 has a pair of guide pulleys 12 and 13 at its top, carried on a winged extension 14 thereof. The rail 11 has a guide pulley 15 carried on a winged extension 16 thereof. The trackways will be fastened by screws or the like to the edges of the window frames.

Each of a pair of carriers 17 (Figs. 5, 6 and 7) carries a pair of anti-friction wheels or rollers 18 journaled on its rear side for engagement with the flanges of the channels in the trackways 10—11 (Figs. 2 and 4), so that these carriers can move up and down freely in the trackways. Each carrier at its lower end has a ledge 19 and an ear 20 that is perforated to receive rope ends 21 and 22 by which the carriers are raised or elevated along the trackways and the window frames. The rope 22 passes over the pulley 15 and the pulley 13, while the rope 21 passes over the pulley 12, these ropes being connected together at their free ends as shown in Fig. 1, so that they can be moved as a unit to raise and lower the carriers simultaneously.

Brackets 24 and 25 for supporting a shade, curtains and drapes are shown in Figs. 8 and 9 and may suitably be of sheet metal having flange-like hooks 26 and 27 respectively, on one face thereof that will receive the edges of the carriers 17. The ledges 19 on the carriers engage the lower ends of these brackets to give vertical support to them. It will be seen that when the ropes 21—22 are drawn downwardly at their outer ends, the carriers together with the brackets 24 and 25 will be raised along the trackways 10—11.

The bracket 24 has hooks 29 for curtain rods and a hole 28 to receive one end of a shade roller, while the bracket 25 has hooks 30 for curtain

rods and a slot 31 for the other end of a shade roller shaft.

The outermost faces of the brackets 24 and 25 have flanges 32 and 33, respectively, into which the edges of drape holders 34 (Fig. 10) will fit. The lower ends of these holders seat on the flanges 19.

The drape holders 34 have ears 35 with holes 36 large enough to receive the stems 37 of drape arms 38. These drape arms can be swung into and out of position across the window as may be desired.

Since the ropes 21-22 are connected to the lower ends of the carriers 17, the window shade that is mounted in the ears 23 and 31 of the brackets, and the curtains which are mounted on curtain rods that will be placed on the hooks 29 and 30, can be raised by the ropes 21-22 high enough to cover the pulleys 12-13-15 that are carried by the upper ends of the rails 10-11. Also by mounting the brackets 24-25 on the carriers 17, at the edges of the window frame, the vertical faces of the frame can be completely covered by curtains and the drapes. The carriers can be supported at various heights by wrapping the free ends of the ropes 21-22 around a hook or the like.

Where there is no wood window frame for attachment of the trackways 10-11, I provide a pair of brackets 40 (Fig. 12) for each trackway rail. One of these brackets will be secured to the wall by a screw driven through a hole 41 at the lower end of each trackway and another one similarly fastened to the wall at the top of each trackway. The lower end of each trackway will be engaged behind a slit and bent clip 42, and the upper end of the trackway will be similarly engaged behind a clip 43, which however will point downwardly. The rails have holes near their upper and lower ends to receive these clips, as shown in rail 10a (Figs. 13 and 14).

In Figs. 15, 16, 17 and 18, I show still another arrangement, which differs from Figs. 1 to 15 primarily in the fact that ropes and pulleys are not employed for raising and lowering of brackets which carry the supporting elements for the shade, curtain rods and drape-supporting rods. A pair of channels 45 are employed, similar to the trackways 10 and 11, for attachment to the edges of the window frame 9. A slide bar 46 is slidably mounted in each channel 45. Near their upper ends, each of a pair of bars 46 has a bracket 47 welded or otherwise secured thereto that is formed to support shade rollers, curtain rods and a drape rod support, the bracket being bent to approximately tubular form at 48 to receive the leg 31 of a drape-supporting rod 38.

At their lower ends, the bars 46 have tab-like extensions 49 which will be grasped by the user to slide the bars 46 vertically in the slideways 45, to thus raise and lower the bracket 47. A yieldable

latch element 50 is provided on the lower end of each channel 45, so that when the brackets 47 are raised to the top of the window frame, the tabs 45 on the bars 46 will snap past the catches 50 and be releasably held thereby in their raised positions.

I claim as my invention:

1. A supporting structure for window curtains and the like, comprising a pair of track rails adapted for mounting at the outer vertical edges of a window frame, the rails being of channel form, a pair of carriers having rollers extending into the channels and movable vertically therein, brackets on the carriers having curtain and shade supporting arms in position to extend across the face of the window frame and toward the window opening, and means for holding the carriers at desired vertical positions relative to the track rails.

2. A supporting structure for window curtains and the like, comprising a pair of guide bars adapted for connection to the outer edges of a window frame, a bracket slidably connected to each of the bars, for vertical movement thereon, the brackets being of generally L-shape in plan view, with one leg of each bracket in position to lie across a portion of the window frame, means on said legs of the brackets, for supporting a window shade and a window curtain, the other leg of each bracket being located at an edge of the frame, and means on said other legs for supporting window drape carrying arms, for swinging movements on vertical axes.

3. A supporting structure for window curtains and the like, comprising a pair of vertical guide rails adapted for mounting adjacent to the vertical edges of a window frame, a pair of vertically-movable carrier plates provided with guiding elements that are engageable with and guided in vertical paths by the rails, curtain rod brackets having telescopic fit with the carrier plates, in a vertical direction, means on the said plates for limiting downward movement of the brackets, on the plates, and means for raising and lowering the carrier plates.

SAMUEL A. VENNARE.
